(57) **CLAIM**

I claim the ornamental design for a wallet having accessory attachment prongs, as shown and described.

DESCRIPTION

FIG. 1 is a perspective view of a wallet having accessory attachment prongs, showing my new design in a folded configuration;

FIG. 2 is a rear perspective view thereof, illustrated in a nearly flat configuration;

FIG. 3 is a front perspective view of FIG. 2;

FIG. 4 is a front elevational view thereof, illustrated in a flat configuration;

FIG. 5 is a rear elevational view of FIG. 4;

FIG. 6 is a right-side elevational view of FIG. 4;

FIG. 7 is a left-side elevational view of FIG. 4;

FIG. 8 is a top plan view of FIG. 4; and,

FIG. 9 is a bottom plan view of FIG. 4.

The broken lines showing a phone and case in FIG. 3 depict environmental matter and form no part of the claimed design. The remaining broken lines represent stitching, and are part of the claimed design.
